PUMP

Kemper P. Brace, South Bend, Ind., assignor to
 International Engineering Corporation, Chi-
 cago, Ill., a corporation of Illinois

Application March 20, 1936, Serial No. 69,879

1 Claim. (Cl. 230—79)

This invention relates to pumps, and is illustrated as embodied in a pump used as an air compressor. An object of the invention is to provide a simple structure of a rotary type, capable of building up higher pressures than a centrifugal pump and yet free from reciprocating parts such as pistons or vanes.

Preferably a liquid is used as the pressure medium of the pump, it being usually arranged 0 in a casing against the outer wall of which it is held by centrifugal force derived from a rotor turning within the casing. The liquid does not fill the casing, and, when it is so thrown outwardly by the rotor, a space about the axis of the casing is left free of liquid. The rotor divides this space into intake and outlet portions, provided with corresponding passages or with other intake and outlet means respectively.

According to an important feature of the invention, the rotor is provided peripherally with a 20 passage, having an intake and an outlet at its opposite ends, and shown as formed by a hollow helix mounted on the periphery of the rotor and driven by the rotor about an axis offset from the 25 axis of the casing. Thus as the rotor is turned, for example by a motor outside the casing having a drive shaft extending into the casing and there drivably engaging the rotor, the intake and outlet ends of the passage are periodically placed 30 in communication respectively with the inlet and outlet portions of the central space. Preferably the rotor has means, such as radial vanes, for causing the desired centrifugal action of the sealing liquid.

35 If desired, the above-described helix can be carried several times around the rotor, decreasing in cross-sectional size toward the outlet end, thereby giving the effect of multistage compression.

40 The above and other objects and features of the invention, including various novel combinations of parts and desirable particular constructions, will be apparent from the following description of the illustrative embodiments shown 45 in the accompanying drawings, in which:

Figure 1 is a view of one embodiment of the 50 compressor in vertical section, with the associated motor shown in side elevation;

Figure 2 is an end elevation of the rotor;

Figure 3 is an elevation of the rotor looking 55 from the right toward the left in Figure 2;

Figure 4 is a view corresponding to Figure 1, but showing a different modification;

Figure 5 is a side elevation of the rotor in 55 Figure 4; and

Figure 6 is an end elevation of the rotor in Figure 4.

In the embodiment of Figures 1 to 3, the compressor comprises a casing 10 having at one end an intake device 12 (either open to the atmosphere or suitably connected with some other source of gas to be compressed), and having at its other end an outlet device 14 adapted to be connected by a suitable conduit with any desired apparatus in which the compressed gas is to be used.

The intake device 12 (unless it is to be open to the atmosphere) is provided with a suitable stuffing box 16 for a drive shaft 18, shown journaled in ball bearings 20 in the end walls of the 15 casing 10. The shaft 18 is arranged to be driven, through any suitable coupling 22, by means such as a motor 24. The devices 12 and 14 communicate with the interior of the casing 10 through suitable openings 26.

The shaft 18 is not coaxial with respect to the 20 casing 10, but is eccentric with respect thereto, being shown above the casing axis. Inside the casing 10, the shaft 18 has rotatably mounted thereon a rotor comprising, as illustrated, a hollow body 28 keyed to the shaft to be rotatably driven thereby. The body 28 has secured about 25 its periphery two approximately parallel flanges or webs 30 and 32, formed to define a hollow helix when sealed as described below, thereby defining 30 a helical passage peripherally of the rotor.

The casing 10 contains a quantity of sealing 35 liquid 34, selected not to react with the gas being compressed, and which in most cases may be water. The flanges 30 and 32 carry means, shown 40 as radial vanes 36 secured between the flanges but with spaces 38 left between them and the periphery of the rotor body 28, for carrying the liquid 34 around with the rotor and imparting to it sufficient centrifugal force to hold it out 45 against the casing 10 in a zone of liquid whose central axis is the axis of the casing 10, some distance below the rotor axis.

Thus the liquid 34 fills the entire space between 50 the flanges 30 and 32 at the top of the casing, but merely seals across their edges at the bottom of the casing, as appears in Figure 1. As shown in Figure 3, the trailing end of the flange 30 overlaps (and may be secured to) the forward end of the flange 32. Thus, since the liquid 34 seals the edges of the flanges all the way around, the rotor itself forms a partition separating an intake space 40 in the right end of the casing (in 55 communication with the intake device 12) from

an outlet space 42 in the left end of the casing (in communication with the outlet device 14).

The only way the gas can go from the space 40 to the space 42 is through the helical passage between the flanges 30 and 32. The liquid between the flanges at the top of the casing serves as the equivalent of a compressor piston, and as the rotor turns it forces the gas along the passage and through the openings 38 to the outlet space 42.

10 The embodiment of Figures 4 to 6 differs from that described above in that the rotor includes a somewhat longer driven body 128, to the periphery of which is secured a single helically arranged flange 130 which passes a number of times around the rotor with a decreasing spacing. Vanes 136 (formed with openings 138 to permit the passage of the compressed gas) are secured to the flange 130 at intervals to impart the desired centrifugal force to the liquid 34.

15 In this embodiment, the successive charges of gas being compressed are moved along the lower part of the rotor, parallel to the rotor axis, in the helical passage defined between the successive turns of the flange 130, during several revolutions of the rotor. As the cross-sectional size

of this passage decreases toward the outlet end, this gives increased compression, and provides what may be regarded as the equivalent of a multi-stage compressor.

16 While two illustrative embodiments have been described in detail, it is not my intention to limit the scope of the invention to those particular embodiments, or otherwise than by the terms of the appended claim.

I claim:

1 A pump having a cylindrical casing containing a liquid and formed with inlet openings in one end and outlet openings in the other end, a rotor comprising a hollow cylindrical body having on its periphery spaced approximately parallel webs 1 and radial vanes secured between said webs and spaced outwardly from the surface of said body to leave a passage between the vanes and said body, the said rotor being seated eccentrically to the axis of the casing acting centrifugally on the 20 liquid to force fluid from the inlet to the outlet openings, and inlet and outlet devices mounted on the ends of the casing over said openings and having respectively inlet and outlet means above said openings.

KEMPER P. BRACE.
